UNITED STATES PATENT OFFICE.

REGINALD NOTON HINCKS, OF VICTORIA, BRITISH COLUMBIA, CANADA.

GOLF CLUB.

Application filed May 31, 1927, Serial No. 195,459. Renewed January 4, 1929.

This invention relates to golf clubs and more specifically to putters and to those for making approach shots, its primary object is to provide a club of this character by which 5 such shots may be made with greater ease and accuracy, and with a feeling of greater certainty as to results than when made with clubs as usually constructed.

In the art of playing golf it is a well recognized fact that the operation of putting, because of its indispensable exactitude, demands a maximum of experienced adroitness from the player and in consequence is a fertile source of handicap and hindrance to all but 15 expert and mature players.

This arises because of the inherent difficulty in correcting the natural swing of the arms by the exact compensating movements necessary to maintain the impelling force in the 20 true direction, and therefore in the avoidance of either pull or slicing effect on the ball. These are the difficulties and defects which my invention and discovery is designed to eliminate or reduce, by providing a club having 25 a right angular offset to the shaft at the neck of the blade, which produces two principal results, one effect being to obtain an initial contact with the ball slightly earlier in the stroke than is now practicable, and the other 30 effect is that in so doing to make more effective use of the further feature of alignment in my improved club and where my invention chiefly resides. This feature consists in providing in the formation of the ironwork, a 35 right angular member which connects the shaft at the neck of the socket to the neck of the blade portion, and which being parallel to the line connecting the centres of the ball and the hole, offers to the eye a sighting factor 40 of great assistance in correctly determining the directive value of the shot. When compared with present methods, where the right angularity must be determined without other aid than mental comparison with the 45 direction of the shaft of the club, the importance of this aid is at once apparent. Moreover in this connection it is to be noted that my club may be successfully used for putting with what is known as the open stance— 50 whereby a firmer position is available to the player—with its accruing advantages.

The invention is more clearly described by reference to the accompanying drawings forming part of this application in which Fig. 55 1 is a side elevation, Fig. 2 is an edge view projected from Fig. 1, and Fig. 3 is a plan

in projection from Fig. 1, the shaft is shown broken off as the invention relates to the shape of the metal portion. Fig. 4 is a perspective view of the entire club.

Taking the drawings in detail and noting that similar numerals in the different views indicate identical parts, 4 indicates the usual socket or hose for the shaft, the narrow extremity of which is continued to the rounded point 5 as a solid member, whence it takes a right angular turn forming the member 6 connecting with the neck of the blade at 7 where it forms a corresponding but opposite rounded point similar to 5 but on the other 60 side of the member which is parallel throughout its length and is right angular to the axis of the shaft 8. The blade 9 may take any of the usual forms providing it is connected to the connecting member 6. The position of the ball in relation to the blade is indicated in 65 Fig. 3 at 10, and it should be noted that the linear character of the sighting member 6 is maintained to the full extent of its length to the point 5, so that the effect of the rectilinear 70 character of the club is sub-consciously impressed upon the player when making his 75 shot.

A further point of practical advantage when making a putting shot with my improved club, is that owing to the slightly longer effective radius of the blade portion over that of the shaft a slightly downward directive 80 tendency is imparted to the shot.

Having now particularly described my invention, I hereby declare that what I claim as new and desire to be protected in by Letters Patent, is:

1. In a golf club having a metal blade and a socket for the reception of the shaft, a sighting 90 guide disposed right angularly to the axis of the said shaft, the said guide connecting the said blade and said socket, the edge of the said blade being spaced apart from the plane of the axis of the said shaft by the 95 length of the said guide.

2. A golf club comprising, a shaft, a socket adapted to receive said shaft and terminating in a solid neck, a blade terminating in a neck, the face of said blade being spaced apart from 100 the axis of said shaft, a member disposed right angularly to the axis of said shaft and connecting the said two necks.

3. A golf club having a blade and a socket for the reception of the shaft, a member of 110 circular cross section connecting the said blade and the said shaft, the axis of the said

member being right angular to the axis of the said shaft, the junctions of the said member with the said socket and the said blade which are intersected by the common plane of the 5 axes of the said member and the said socket being right angular whereby the directive effect of the outline of the said member is retained at a maximum value.

4. A golf club having a metal blade and a 10 socket for the reception of the shaft in which

the axis of the said shaft is parallel to the edge of the said blade, an extension member of circular cross section uniting the neck of said blade with the said socket, the axis of said member being right angular to the axis 15 of said socket, the playing face of the said blade being within the right angle formed by the said blade and the said member.

REG. N. HINCKS.
